PUNCHING MACHINE

William W. Lasker, Brooklyn, N. Y., assignor to
 Remington Rand Inc., Buffalo, N. Y., a corporation of Delaware

Application June 13, 1932, Serial No. 616,926

2 Claims. (Cl. 164—114)

My invention relates to card punching or perforating mechanism and, more particularly, to improvements in punching machines of the type of the well known Powers duplicating punch of commerce.

Duplicating machines, as now constructed, while highly efficient for the purposes for which they are designed, are all limited as regards range of operations and, furthermore, are susceptible of improvement as regards control of the operations of which they are capable.

With the foregoing in mind, the principal object of my invention, generally stated, is to equip a machine of the above designated type for a wider range of operations, as compared with duplicating control of all operations which the machine is capable of performing.

Specifically, the particular object of my invention is to provide an efficient, simplified machine, operative under the control, primarily, of a master, or pattern card, to automatically punch in a tabulating card data representing perforations of the master card, and adapted for variable operation to duplicate the master card perforations, enter in whole, or in selected part, on either one, or a series, of tabulating cards, and either in the master card, or in different locations, as desired.

Another object is to provide for punching in the tabulating card or cards, other, or later data, representing perforations not punched in the master card controlling the first punching operation.

Another object is to provide a machine operative to punch, under the control of a master card, or a series thereof, a plurality of sets, or series, of tabulating cards of selected numbers in each set, or series, and means for automatically stopping the machine when the punching of each set or series has been completed.

My invention furthermore comprises a duplicating punch including a field of sensing pins operative under control of a master card to set punch setting gags of a corresponding gag field, together with means for disabling selected sensing pins to render them ineffective as regards setting corresponding gags, and means for retaining a selected set-up of gags for repeat operations of the punches set by the latter.

Still other objects of my invention are to provide for automatically disabling the entire field of sensing pins when a record card is not in controlling position, retaining a selected set-up of punch gags under such conditions, providing in conjunction with master and tabulating card feed

receptacles, respectively, mechanism for automatically stopping the machine when the supply of cards is exhausted from either of said receptacles, together with means for disabling at will the stopping means, associated with the master card feeding receptacle, and equipping the machine for retaining, under the control of a single key, a gag set-up extending throughout the entire field of punch setting gags.

Still another object is to provide manipulative means for disabling complementary sensing pins and punch gags at will.

Other objects, together with the structural details of the invention, will be apparent when the following description and claims are read in conjunction with the accompanying drawings, in which:

Fig. 1 is a view in front elevation of a duplicating punch constructed according to my invention.

Fig. 2 is a detail view in front elevation of substantially the upper half of the machine with parts broken away and shown in section, and other parts eliminated for the sake of clearness of illustration.

Fig. 3 is a similar view of the lower half of the machine.

Fig. 4 is a vertical section taken on the line 4—4 of Fig. 2, looking in the direction indicated by the arrows and with parts of the machine shown in elevation.

Fig. 5 is an elevational view taken on the line 5—5 of Fig. 3.

Fig. 6 is a fragmentary isometric view of sensing mechanism with which the machine is equipped.

Fig. 7 is an isometric view of the sensing mechanism, means for ejecting a card therefrom, means for disabling the entire field of sensing pins, when a record card is not in controlling position, and means for disabling selected sensing pins of said field.

Fig. 8 is an isometric view looking at the side opposite to Fig. 7, and showing part of the driving mechanism for the sensing mechanism.

Fig. 9 is an isometric view of mechanism for removably mounting a multiple translator in the machine, a trip key for controlling starting and stopping of the machine, an interlock between said mechanism and key, parts of a field of punch gags set by said translator, and a retract bail associated with said field of gags.

Fig. 10 is an isometric view of automatic card numbering and card counting mechanism, respectively, and means for disabling the same.

Fig. 24 is a perspective view of my invention with the multiple translator removed.

Fig. 25 is another view of part of the mechanism shown in Fig. 22.

For the purpose of description the machine of my invention may be considered as comprising three main units, to wit, a head or sensing unit 10, an intermediate or translator unit 11, and a base or punching unit 12.

55 The head or sensing unit

Referring now to Figs. 1, 2, 4 to 8, 22 and 24, the head or sensing component comprises a sensing box, or frame 58, a field of sensing pins 13 mounted in said box in columnar rows for independent vertical movement and normally projecting below said box, pin tensioning springs 110 interposed between the top of the box and enlargements 111 on said pins, respectively, to yieldingly hold said pins in normal depressed position, and a series of pin locking slides 14, one for each row of pins, endwise movable in opposite directions to locking and unlocking positions, respectively. Leaf springs 69 secured to said box 58 and engaging notches 113 in the slides 14, urge the latter toward locking position. The slides 14 are provided with slots 114 and V-shaped noses 115 therein and the pins 13 with locking studs 116 the arrangement of these parts being such that the pins 13 may be locked, by cooperation of said studs and noses, in either elevated or depressed position,

relative to the sensing box 58. The noses 115 are shaped as described to reduce frictional resistance between the same and the studs 116 for obvious reasons. In this connection, the leaf springs 69 are stronger than the combined springs 110 of their related slides 14 to prevent movement of said slides by tensioned pins 13.

The above described sensing pins and locking slides are substantially the same as those disclosed in my co-pending application S. N. 538,429, filed May 19, 1931, to which attention is invited.

The sensing box, or frame, 58 is mounted, as by sleeves 111 (Fig. 4) and guide rods 118, for vertical reciprocation between the upper ends of side frame members of a supporting structure comprising in the present invention legs 30 (Figs. 1 and 24), a base plate 31 and pairs of lower, intermediate and upper sections 32, 35 and 36 (Figs. 4 and 24), respectively, forming the said frame members.

In the normal elevated position of the sensing box 58 the locking slides 14 are held in retracted unlocking position as follows:

Suitably mounted on the rear side of said box, is a rock shaft 71 having fast thereon arms 70 connected by a rod 72 (Figs. 6 and 8) to form a bail engaging said slides and retracting them to unlocking position. The said bail is held in a slide retracting position by means of arms 73 fast on the shaft 71 and stationary cams 74 and 74' engaged by said arms. Springs 119 connected to arms 73 and to the box 58 urge said bail toward a slide releasing position. In the retracted position of the slides 14 the pins 13 are freely movable, the studs 116 playing in the slots 114.

Figs. 19 and 20 show means for manually disabling individual interponents 20. A bar 170 of angular cross section is mounted by suitable shoulder screws 172 disposed in slanting slots 181 below interponents 20, springs 175 at each end of the bar retain the bar in a normal elevated position, shown by solid lines in Fig. 19. In this position, toes 163 engage the upper surface of 170 which prevents further rotation of said interponents. When desired, bar 170 may be pressed downward by the fingers permitting the turning of interponents 20 to inoperative position.

Suitably mounted at opposite sides of the box 58 are master card supply and storage receptacles 37 and 38, respectively. A master card is fed from the supply-receptacle 37 into a sensing chamber 19, (Figs. 2, 4 and 19) formed beneath the box 58 by perforated plates 120 and 121, in which chamber it is temporarily located by a card stop 66 so that any or all of said pins 13 can pass through perforations in said card. Subsequently, the master card is ejected from said chamber 19 into the storage receptacle 38. The mechanism for reciprocating the box 58, and feeding and ejecting the card will presently be described.

While the sensing box 58 is descending, the pins 13 search for perforations in the master card. The pins, which do not find perforations are restrained from further movement by the card. After those pins, which have found perforations have passed a predetermined distance below the card, the arms 13 ride off cams 74 and 74' thereby permitting the rod 72 to move to slide releasing position, under the urge of the spring 119, and the slides to move to unlocking position under the action of the springs 69. At this time, pins 13 which have not found perforations in the master card have their locking studs 116 elevated above the noses 115 and are locked thereby in elevated position, whereas the studs of the pins which have

found perforations are located beneath said noses and their pins are locked thereby in normal depressed position. Continued downward movement of the sensing box 58 will cause these pins 13 which have been locked in normal depressed position to engage and depress related interponents 15 of a field of the latter suitably mounted in the head or sensing component 10 for depression against tensioning springs 122.

10 The interponents 15 are operatively related to translator rods 16 of the intermediate or translator component 11 to set punch gags 17 for a field of punches—arranged in the punching unit 12, in correspondence with the arrangement of 15 the sensing pins 13.

15 In the event that there is no master card in the sensing chamber 19 it is essential that the locking slides 14 be disabled against movement to locking position, otherwise all of the sensing pins 13 would be locked in depressed position, and all of the punch gags 17 set thereby. To obviate this 20 contingency, means for disabling the locking slides 14 are provided as follows: A pin 67 (Fig. 6) is mounted on the box 58, as by the bracket 61, to be engaged by an edge of a card located in the sensing chamber 19 and for elevation by said card. A tensioned lever 68 is pivoted, as at 123, on the box 58, to block movement of one of the arms 70, and thereby lock the slide retracting bail against 25 movement to slide releasing position. When there is no card in the chamber 19, said lever 68 is in blocking position. The pin 67 is operatively connected to said lever to move the latter to ineffective position when said pin is elevated by the 30 presence of a card in said chamber.

35 The relative strength of the interponent tensioning spring 122 and the pin tensioning springs 110 is such that the former overcome the latter so that none of the interponents 15 are depressed by the pins 13 when the locking slides 14 are disabled.

40 Associated with the locking slides 14 (Figs. 6 and 18) are manually manipulative devices for disabling a selected columnar row or rows of sensing pins 13, and comprising a series of sliding keys 40, one for each locking slide 14, suitably mounted on the box 58 for cooperation with notches 125 in the slides 14 to lock the latter in retracted position. The sliding keys 40 are for 45 use when it is desired to prevent the repetition of data in a certain row or rows of the master card being sensed. Since, as has been explained, the pins 13 are freely movable in the retracted locking position of the slides 14, when the latter are 50 locked by said keys 40, the related pins 13 which find perforations in a master card are ineffective relative to the interponents 15, and, hence to the punch gags 17 also.

55 The master card which controls the setting of the gags 17 may be held in the sensing chamber 19 for a determinate plurality of reciprocations of the sensing mechanism, so that the gags 17 will be set and reset for a corresponding plurality of cycles, thus effecting the punching of a corresponding number of cards which may be replicas of the card sensed by the pins 13. Normally the locking slides 18 are released at the end of each 60 operation by a reciprocation of a universal retract bar operating on the cam portions 20' of the retract interponents 20. One or more of the retracting interponents 20 may be turned out of the path of the universal retract bar 54 by a manual operation as is diagrammatically indicated in Figures 3, 19 and 24 so that some, and only some, of the locking slides 18 will be released by the said

retract bar. Therefore, if a gag (or gags) 17 is depressed in those columns of the card corresponding to ineffective interponents a repetition of certain data may be punched in the cards passing through the punching chamber, even if the corresponding field (or fields) in the master control card are blank. It will also be understood that the translator interpreters 16 of the intermediate component may be offset or transposed in various ways as is well known in the art of 10 multiple translators, so that, for example, entire fields of the master card may be transposed. It may be desirable to transpose the perforations which occur in an upper ninety column field to a lower ninety column field when duplicating 15 cards such as those which may have been punched by the device of my co-pending application, Serial No. 537,831, filed May 16, 1931. It may be desirable to transpose perforations representing debits and credits along with the corresponding 20 control holes of cards, such as those illustrated in the co-pending application of Wegener, Serial No. 504,336, filed December 23, 1930. It is obvious that a partially perforated master card may be fed into the sensing chamber, and certain of 25 the gags 17 set; then the corresponding retractor interponents 20 disabled and thereafter a second master card may be fed into the sensing chamber to set other gags 17, and in this way 30 reproduce data which has been perforated on a plurality of master cards.

A predetermined number counter designated generally at 21 (Figs. 1, 14 and 24) may be set to a predetermined indication and the machine will automatically operate to perforate replicas of the 35 card in the sensing chamber of the head, until the pre-set number has been reached.

The machine is started by depressing a trip key 22 (Figs. 1, 12 and 24). A depression of this key releases the main driving clutch and the 40 machine will continue to operate until stopped by again depressing the start key 22, or by an equivalent automatic operation controlled by the usual presence of card detecting pins of the 45 card magazines, or by the predetermined numbering device 21. It may sometimes be desirable to consecutively number the cards which are being perforated. This may be effected by 50 depressing the numbering key 23 (Figs. 1, 10 and 24).

55 It is sometimes desirable to set the gags 17 under control of a master card, then hold the gags in depressed position by disabling the universal retract bar when it is desired to have many hundreds or many thousands of cards having identical characteristics. This may be done by 60 depressing the retract control key 24, and shifting the "presence of card" sensing lever 25 (Figs. 1, 9, 11, and 12). The lever 25 disables the card presence detecting pin of the master 65 card magazine.

The multiple translator is an interchangeable unit as in the familiar Powers tabulating machines, and special provision is made for readily interchanging differing translators, as will be described in greater detail hereinafter

Framework

The framework of the machine may be of any suitable form and material. For purposes of 70 illustration the machine has been shown as supported by a plurality of legs 30 attached to a main base plate or table 31 (Figs. 1, 3, 5 and 24) which supports the entire machine. The mechanism of the base member of the system is sup- 75

ported and carried by the usual side frames 32 attached to the base plate or table 31; also carried by the frames 32 is a supporting mechanism for the blank card receiver 33 and the discharge receptacle 34. Mounted on the side frames 32 is a pair of intermediate frames 35 which forms spacers for the positioning of the multiple translator and for supporting the head 10 of the machine. Carried by the frames 35 are the side frames 36 of the head of the machine. The said side frames 36 are bound together by suitable ties and said frames, like the frames 32, carry the master controlling card receptacle 37 and the corresponding discharge receptacle 38 (Fig. 2). The entire framing so far described, may be protected or hidden by a suitable case shown in Figure 1. It is desirable to have access to a series of latch controlling members 40 (see also Figs. 1, 6, 18, 22 and 24). To this end the casing is provided with a hinged lid 41. The case may also be provided with shelves 42 for supporting desired objects, such as stock cards. The multiple translator may be built in a manner analogous to the familiar tabulator multiple translators.

Main driving mechanism

The main shaft of the machine may be driven in any suitable manner, such as by an electric motor M (Fig. 24) for rotating the free member 43 of a clutch (Figs. 12, 13 and 24). Said clutch may be of any suitable construction such as, for example, that shown in my Patent No. 1,810,317, granted June 16, 1931. One member of said clutch is fixed to the main shaft 44 (Figs. 3 and 5) for operating the mechanism of the base component. At one end of said shaft 44 is a sprocket wheel which may be connected in a suitable manner, such as a silent chain, to the sprocket wheel 45 (Figs. 4, 8 and 24) fastened to the main shaft 46 of the head of the machine. Said chain passes over a tensioning idler as shown in Fig. 24, rigid with the shaft 47 (Fig. 14) and which may be used for operating the predetermined counter mechanism step by step. The two main shafts 44 and 46 rotate in the same direction at equal speeds. The main shaft 44 of the base is provided with an eccentric 100 (Figs. 3 and 5) for oscillating the rocker arm 49 (Fig. 3) for driving a picker 39 to feed blank cards seriatim from the bottom of the weighted stack in the stock magazine 33. A series of continuously rotating feed and skid rolls 48 are provided for feeding the card into the punching chamber, thence rearwardly, after the card has been perforated, through a pair of continuously rotating ejecting rolls to a receiving magazine 34. The entire series of rolls 48 are geared to the shaft 44 and the upper roller of each pair is held resiliently in contact with the lower roller of the pair in the well known manner. Fast to said main shaft 44 is a cam 99 for rocking the spring pressed arm 50 for interposing a card stop 60' at the proper time into the path of the card in the punching chamber so that it will remain stationary during the perforating operation, and then withdraw said card stop to permit the perforated card to be ejected into the storage magazine 34. The die block 51 is caused to move upwardly then downwardly by means of a suitable cam 101 (Fig. 5) fixed to the shaft 44 in the manner well known in the art, for the purpose of forcing the blank card against those punches which are held against upward movement by depressed gags 17 as has been previously

described herein above. Also fast to the shaft 44 is a cam 52 which may (or may not) reciprocate a line 53 (Fig. 15) for operating universal retractor bar 54. The operation of the link 53 is determined by the position of the retract control key 24 as will be described more fully herein-after. A shaft 26 (Fig. 10) is connected to the main shaft 44 in a suitable manner, such as by a chain, for rocking a bell crank 27 to effect the printing of consecutive numbers on the perforated card.

Fixed to the stub shaft 47 (Fig. 14) is an eccentric for reciprocating the link 55 for driving the predetermined numbering counter step by step.

The main shaft 46 of the head component is provided with a pair of cams 56 for rocking levers 57 for reciprocating the sensing head 58 (Figs. 4, 6, 7 and 8). The levers 57 are held in contact with the cams 56 by a pair of stout springs 60 (Figs. 4 and 7) anchored to a stationary bar at the extreme top of the machine. The tension of said springs 60, which hold levers 57 in contact with their cams, tends to elevate the sensing head mechanism 58. Also fixed to said shaft 46 is a gear 61 (Fig. 7) which drives the series of pairs of feed rolls 62 through a train of spur gears shown in Figs. 6 and 7. The operation of the rolls 62 corresponds to the above described rolls 48, and will not be further described. Also fixed to the shaft 46 is a cam 63 for oscillating a spring pressed lever 64 (Fig. 8) which oscillates the card stop shaft 65 through a link and crank mechanism for positioning card stops 66 to temporarily hold a master card in the sensing chamber of the head component.

It may happen that the master card to be sensed is perforated in both upper and lower fields and it may be desired to disable one or the other, or both co-columnar fields. The construction for effecting such operations is diagrammatically illustrated in Figure 22. It will be seen in said figure that each column of sensing pins 13 is provided with two slides 14 and each of said slides is provided with a manipulative locking slide 40 and that each slide 14 is effective on only half of a column of pins 13. The sensing pins 13 are arranged "right and left"; that is to say the locking pins of half the said sensing pins extend in one direction and the remaining half have their locking pins extending in the opposite direction. Portions of one of the locking slides 14 are cut away to provide room for the springs and locking slides of the other slide.

It is obvious from the foregoing description that applicant could use more or fewer pins 13 to a column in the sensing head 58 than shown in the accompanying drawings. It is to be understood that the number shown is merely an illustrative use of the invention described herein. Further the number of horizontal fields may exceed the two described in the last paragraph.

Multiple translator

The multiple translator indicated at 11 in Figures 1, 2 and 3 closely resembles the usual tabulator multiple translator. It consists essentially of an open ended box-like frame whose ends are provided with assembled grids for guiding the ends of a series of translators 16 (Figs. 2 and 3). The said translators may be arranged so as to transpose certain fields, or to repeat certain indicia by Y-wires as is well known in the multiple translator art. If desired a certain field or fields

of translators 16 may be transposed so that 0, 1, 2, etc., on the master card will become 9, 8, 7, etc., on the card to be punched, thus reversing a certain field or fields as the case may be.

- 5 The multiple translators are arranged so as to be interchangeable and thereby greatly increase the utility of a duplicating punch. The bottom of the multiple translator is provided with flanges which fit into rabbeted grooves of the blocks 75 (Figures 9 and 24). The blocks 75 are slidably mounted on the frame supported screws 18, and are normally urged upwardly by strong springs; but said blocks are normally held against the spring tensions by resiliently urged locking slides 76. When it is desired to remove one of the translators a finger piece 77 is rocked upwardly and arms fixed to the shaft carrying the finger piece 77 move rearwardly carrying with them the locking slides 76 which have narrowed grooves fitting under shoulders on the said screws 18. (See Fig. 23.) As soon as the rabbeted blocks 75 are elevated to the limit permitted by screws 18 (this is the position in Fig. 9) the multiple translator 11 may be removed in the ordinary way by the manually controlled pinch latches at the lower forward edge thereof as is well understood in the art. When a new multiple translator is slid into the machine and locked by its pinch latches to the rabbeted blocks 75 the lever 80 is depressed until the springs of the locking slides 76 snap under the shoulders on the screws 18. The lever 80 is fixed to a shaft near the rear of the machine; said shaft also carries a forwardly extending arm at the end remote from lever 80 so that when said shaft is rocked the said lever 80 and the arm thereon coacts with projections on the rabbeted slides 75 to force both of them down simultaneously, thus locking the new multiple translator into operative position.

40 Predetermined counter

The predetermined counter is best shown in Figure 14. It consists of a pair of ratchet discs 81, each of which is fast to a sleeve extending outwardly to a pair of manually manipulative knobs or dial buttons, so that each may be independently set to a predetermined position. One of the discs 81 is provided with one hundred ratchet teeth. The one hundredth tooth space is of substantially double depth. The other disc is provided with about one dozen teeth. A scale plate 82 is provided having an opening for reading the graduations on the hundredth toothed disc and a pointer for indicating the position of the other disc. The said discs are held against accidental displacement by a usual form of spring-pressed retaining pawl. A radius arm 83 carries a spring-pressed operating ratchet for the discs 81. The radius arm 83 is connected by a link 85 to an eccentric strap surrounding an eccentric fast to the idler shaft 47 so that each time the idler shaft 47 makes a complete revolution (or what is the same thing one card is perforated) the hundredth toothed disc 81 is advanced one ratchet tooth and when it has advanced an amount corresponding to one hundred teeth the actuating pawl falls into the deep notch and the next rotation of shaft 47 advances both the ratchet discs one tooth simultaneously and thereafter advances the hundredth tooth disc a single tooth at a time until it has completed another complete rotation. When both discs 81 have been rotated to their zero positions the next operation causes a projection on the disc having the fewer ratchet teeth to positively rock an offset bell

crank 84 to shift the core of a Bowden wire to disable the main driving clutch thus stopping the machine after a predetermined number of replica cards have been perforated.

Trip key

5

In order to start operation of the machine the trip key 22 (see Figs. 9, 12, 13 and 14) is depressed. When it is desired to stop the machine the same key 22 is depressed. The machine is automatically stopped if the stock cards in either magazine 33 or 37 become exhausted, or if a predetermined number of cards have been perforated. The machine is driven through any suitable form of clutch 43. The said clutch may be, for example, that disclosed in the patent to Lasker, 1,810,317, granted June 16, 1931. The free member of the clutch 43 is normally held against rotation by a buffered stop plunger 89, Figs. 12 and 13, which in turn is pivoted to the top arm of a spring pressed irregular cruciform lever 86. When the trip key 22 is depressed, a bell crank integral therewith, depresses a spring pressed plunger, which in turn shifts the wipe-slide 87 downwardly to rock the cruciform lever 86; and when said lever 86 has been rocked by the wipe-slide 87 a distance sufficient to withdraw the buffered plunger 89, a pin 88 thereon is engaged by a notch on the spring pressed inverted T shaped lever 90 and is thereby held in shifted position as is best shown in Figure 13. Comparison of Figures 12 and 13 shows that the wipe-slide 87 is shifted slightly towards the clutch 43, such shifting, however, being only to an extent sufficient to cause the wipe-slide 87 to miss a projection on cruciform lever 86 when the trip key 22 is again depressed. Depression of key 22 will now cause the lower end of wipe-slide 87 to contact with a shelf or ledge on the inverted T shaped locking lever 90. The contact between members 87 and 90 causes the latter to be rocked slightly clockwise, thus releasing the irregular cruciform lever 86. It is thus seen that a first depression of key 22 will set the machine into operation, and a second depression thereof will stop the machine.

The inverted T shaped lever 90 carries a pin extending perpendicular thereto which lies in the path of a pivoted lever 91, Fig. 12. The lever 91 has pivoted near its extreme end a feeling plunger for detecting the presence of stock cards in the magazine 33. When the cards in said magazine 33 become exhausted, the feeling finger attached to lever 90 will rise under the influence of a suitably located spring, thus depressing the pin attached to inverted T shaped lever 90 to release the cruciform lever 86 and thus stop the machine.

Similarly the upper or master card magazine 37 is provided with a spring urged lever 92, a spring therefor, and a sensing pin. The said lever 92 is connected through link and bell crank mechanism to a bell crank along side the lever 91 so that when the magazine 37 becomes exhausted the pin on latch lever 90 will be rocked as before, and thus stop the machine. Sometimes it is desirable to permit the machine to operate even after the magazine 37 is exhausted. This may be effected by simply holding the lever 92 in the position shown in Figure 12. A special key or lever 25 (see also Figure 11), which has the form of an offset bell crank pivoted in the casing of the machine, has a laterally extending stud overlying the lever 92. The key 25 as shown in Figure 11, permits lever 92 to stop the

75

machine. However, if it is shifted clockwise, the stud thereon will hold lever 92 depressed, and thus disable the sensing pin of the upper magazine 31.

5 The core of a Bowden wire 180 is connected in any suitable manner to the stud on inverted T shaped latch member 90 so that when the core of said cable is drawn downwardly (as viewed in Fig. 12) the machine will be stopped as above described. The core of said Bowden wire is connected to the stopping lever 84 of the predetermined counting mechanism shown in Figure 15.

Numbering mechanism

15 It is sometimes desirable to count the number of cards which are perforated by the machine, and to print consecutive serial numbers on the cards just after they have been perforated. This mechanism is in the nature of an optional attachment and is similar to that fully shown and described in the patent to Lasker 1,855,133, granted April 9, 1932. This mechanism is best shown in Figures 10, 16 and 17. A numbering head 93 is carried by a sturdy rocker frame 29 which is normally urged upwardly by a strong spring (not shown). Said frame is pivoted to the upper plate of a printing chamber located just beyond the pair of eject rolls 48. When the numbering attachment is included with the machine it will be understood that the receiving magazine 34 (Figure 3) is located beyond the printing chamber as is well known in the art. Pivoted near the supported numbering head 93 is a spring urged hook 28 which is normally engaged by the bell 35 crank 27, which in turn is oscillated by the shaft 26 rotating in synchronism with the main shaft 44. Therefore, every time that the main shaft and the head shaft 26 complete a rotation the hook 28 is drawn downwardly to impress the 40 number at printing position on the numbering head 93 on to the edge of the card in the printing chamber. Any suitable form of inking ribbon mechanism may be associated with the numbering head 93. Such mechanism is indicated 45 generally at 98.

The upper end of the spring pressed frame 29 is connected by a link to a frame supported offset bell crank 84 Fig. 10, which in turn is connected in any suitable manner to the crank of a consecutive counting device 84. Therefore, the consecutive counter 84 will be operated for each and every rotation of the shaft 26 if the hook 28 engages the arm 27. If it is desired to disable the numbering mechanism the key 23 is depressed. The stem of said key extends rearwardly to a pivot on a frame supported offset bell crank, one arm of which carries the spring pressed latch 43, so that while the said key 23 is being depressed the latch 43 will snap under a projection on the hook 28, then continued movement of the key 23 will disable the connection between hook 28 and arm 27. There is a notch in the stem of the key 23 for holding it in depressed position. The actuating means for numbering head 93 is best shown in Figure 17. It consists of a suitable crank fixed to the actuating shaft of the numbering head, having a pin which fits into an elongated slot of a bracket 95 fastened on top of the printing chamber. When the spring pressed frame 29 is shifted upwardly and downwardly during a printing operation, the said crank attached to the shaft of the numbering head is oscillated to advance the units wheel of said numbering head one step. Each numbering head is provided with a plate for guiding and sup-

porting it in a pair of rabbeted grooves, as is clearly illustrated in Figure 16. If desired the numbering heads may be differently located on the differing supporting plates, as is illustrated by comparison of Figures 16 and 17, so that one numbering head will print its numbers near the margin of the perforated cards, and the other will print its numbers further from the card margin. The differing numbering heads may be identified by suitable indicia such as "1" and "2", as is indicated in Figures 16 and 17 respectively. A suitable snap lock, or clamping screw such as illustrated in Fig. 16 may be used to lock any numbering head inserted into the spring urged rocking frame 29.

15

Retract key

When the predetermined counting mechanism shown in Figure 14 is set for operation, it is necessary to disable the retract mechanism which operates upon the retracting interponents 20 of the punch, Figures 3, 15, 18 and 19. The retract mechanism comprises a cam 52 fast on the main shaft 44, which is adapted to shift a strut 53 (Figure 15) upwardly to rock a shaft 97 which carries the retract bar 54. The retract bar 54 wipes over the camming surface of the retract interponents 20 to shift the locking slides 18 against their springs to release any gags 17 which may have been set or depressed. This is the 30 normal operation of the machine when each card fed through the head is duplicated by the punches in the base. When constructing a group of replicas the strut 53 is shifted out of the path of the cam 52 by a sliding key 24, which has a 35 notch embracing the said strut 53. The key slide 24 is resiliently held in either of two positions, the active and the inactive, by a suitably located spring urged pawl.

40

Timing

The times at which the movements of the sensing pins 13; the die 51; the master card; occur and the blank card is punched are shown diagrammatically in Figure 20. The timing diagram is really two super-imposed diagrams, the one for the head, the other for the base. A cursory examination shows that the sensing pins and the die have approximately the same extents of movement but in opposite directions 50 with a phase difference of approximately 160° lag for the die. Similarly the movement of the master card with respect to the blank card to be perforated differs in phase approximately 140° lag for the blank. The timing diagram illustrates two complete cycles of the machine as is indicated by the two series of abscissa running to 360°.

45

50

55

60

65

70

75

Following the master card it is found that the card is picked after a movement of about 10°. At about 110° the master card enters the feed rolls 62, and reaches the sensing chamber at about 170°. While the card is still moving the sensing pins 13 begin to move downwardly to sense the master card, but before an appreciable movement of said pins has occurred, the card reaches the card stop (about 270°). The card is then at rest and remains at rest for a period of about 230°. After the card has been at rest for about 40° the sensing pins 13 which have found perforations in the master card are locked and the continued downward movement of said pins results in the setting and latching of the gags 17 at about 60° of the second cycle. The die starts upward to punch the blank card

75

shortly before the gags 17 are set. The sensing pins remain at rest in their lowest position for a period of about 10° when they start upward, and are released at about 110° of the second cycle. The punches touch the blank card shortly after the gags 17 have been set and punching occurs shortly after the sensing pins 13 have been released. At about 140° of the second cycle the card stop is withdrawn while the pins are still moving upwardly; the master card is being fed into the eject rolls; and finally the card clears the eject rolls at about 200° of the second cycle slightly before the die reaches its maximum elevation. The blank card in the base of the machine has very nearly the same sequence of movements, except that it is lagging about 140° in phase. The die has approximately the same timing as that of the sensing pins just described, except that it lags approximately the same 140° behind the sensing pins.

Two cards, one in the head and one in the base of the machine, are moved at the same time. This is indicated at the top and bottom parts of the timing diagram, where a repetition of the described timing occurs. Thus the legend "machines stops" occurs at 360° as well as at 0°. Inspection shows that this and the other legends pertaining to the card are retarded 360° in phase, so that one card is being picked up and fed into the feeding rolls while the other card is at rest in the sensing chamber and, further that the second card enters the sensing chamber very shortly after the card stop has been withdrawn

and the sensed card is being fed to the ejecting rolls. Similarly the bottom of the diagram shows the progress of a second blank card which overlaps the progress of the card which is in the punching chamber. This overlapping of the progress of cards results in a considerable increase in the work performed by the machine.

5

What I claim as new and desire to secure by Letters Patent is:

1. In a machine of the class described, the combination of a field of record sensing means, a corresponding gag-field controlled thereby for rendering corresponding punches active, means operable in accordance with the presence or absence of a record for enabling or disabling the sensing means control, and means including a key controlled bail for retaining the activity of the punches notwithstanding the disablement of the sensing means.

2. In a machine of the class described, the combination of a field of record sensing means, a corresponding gag-field controlled thereby for rendering corresponding punches active, means operable in accordance with the presence or absence of a record for enabling or disabling the sensing means control, and means including manipulatively adjustable interponents adapted to cooperate with locking slides for controlling the gags of a gag-field for retaining the activity of the punches notwithstanding the disablement of the sensing means due to the absence of a record.

WILLIAM W. LASKER.
